A. E. LINEBERG.

CAR REPLACER.

APPLICATION FILED JULY 7, 1914.

1,137,641.

Patented Apr. 27, 1915.

UNITED STATES PATENT OFFICE.

ALBERT ELLISON LINEBERG, OF WILKES-BARRE, PENNSYLVANIA.

CAR-REPLACER.

1,137,641.

Specification of Letters Patent. Patented Apr. 27, 1915.

Application filed July 7, 1914. Serial No. 849,394.

To all whom it may concern:

Be it known that I, ALBERT E. LINEBERG, residing at Wilkes-Barre, in the county of Luzerne and State of Pennsylvania, have invented a new and Improved Car-Replacer, of which the following is a specification.

My invention has for its object to provide a new and improved means of a simple and economical construction, for replacing street 10 cars or other railroad equipment on the track when derailed.

Another object of my invention is to provide a car replacing means capable of being easily manipulated and adjusted for 15 effecting the desired operation in a manner that meets all of the requirements and conditions necessary to guide the wheel flange onto the car rail without slipping or lost motion.

With other objects in view that will hereinafter appear, my invention comprises a car replacing means that embodies the peculiar construction and novel arrangement 20 of the parts, all of which will be hereinafter fully explained, specifically pointed out in the claims, and illustrated in the accompanying drawing, in which:

Figure 1 is a perspective view of my invention, the same being shown in operative 30 position. Fig. 2 is a transverse section thereof on the line 2—2 on Fig. 1, the spherical ball or bearing member being shown in place. Fig. 3 is an inverted plan view of the replacer, the ball rest or bearing member 35 being omitted and Fig. 4 is a detail view of the ball rest or bearing member hereinafter referred to.

In the practical construction, my replacing means consists of an elliptical body 1 of 40 any suitable material, preferably steel, and it is of such cross sectional shape that when placed next to the rail onto which the car wheel is to be replaced, the top surface thereof is higher than the rail. By referring more particularly to Figs. 2 and 3, it 45 will be noticed that the inner or rear face 12 of the said body extends longitudinally and in an approximately vertical direction and is concaved to form, as it were, a recess 13 in the said rear face 12, the opposite ends of which terminate in straight or vertical edges 14. Between the said edges 14 the wall of the concaved portion inclines downwardly 50 from the top to the bottom, as is shown in Fig. 2. The under side of the body 1 is formed with a central concaved seat 3, which

is located directly under the top or crown 11 of the said body, and the said seat 3 communicates with the recess or side concavity 13, through the arched shape transverse 60 opening 15 (see Fig. 2).

By reason of the peculiar construction of the replacer, so far as described, the same presents a large circular surface that serves, as it were, as a table on which to ride the 65 flange of the car wheel, and since the wheel flange has ample room for movement on the upper face of the body 1, the said wheel can be readily directed toward the top or crown portion 11.

The peculiar construction of the inner side 70 of the replacer 1, and particularly of the concaved face, is such that as soon as the wheel flange is forced beyond the crown 11 of the body in the direction of the arrow X 75 onto the downwardly inclined portion 18 of the upper face between the crown 11 and the concaved wall, its flange will slide into the concaved recess and in doing so, it will engage the outwardly inclined vertical wall 80 of the said concaved portion and be thereby forced over to bring the wheel tread onto the rail.

4 designates what I term a ball bearing and it has an attached pull chain 30. The 85 bearing 4, when placed to fit within the pocket 3 of the body 1, acts as a fulcrum for the replacer and tends to lift the outer edge of the said body off the ground. The bearing 4, it should be stated, is intended for use 90 only under such conditions where it is desirable and advantageous to have the replacer body 1 rockably supported so that the said body 1 may be readily tipped in any direction desired. The lower outer edge of the 95 body hits projections 19 for gripping into the ground to firmly hold the body 1 in the applied position. To lighten the weight of the body 1, the same is cored out on the under side to form radial pockets 16 (see 100 Fig. 3).

It is understood that the replacer may be made of various sizes to suit the conditions under which it may be employed and, when using the bearing 3, the chain attached 105 thereto extends through the arched passage at the concaved side and may be readily utilized for pulling and tilting the body 1, as conditions may make necessary.

What I claim is:

1. A car replacer comprising a body having a flat base and an upper convexed face,

- said upper face including a crown portion midway the ends of the body and adjacent one side thereof, the said side of the body being extended in the longitudinal direction 5 of the body and including a convexed vertical wall, the upper face of the said body also including a downwardly inclined portion that extends from the crown portion to the upper edge of the said concaved wall.
- 10 2. A car replacer comprising a body having a flat base and an upper convexed face, said upper face including a crown portion midway the ends of the body and adjacent one side thereof, the said side of the body 15 being extended in the longitudinal direction

of the body and including a convexed vertical wall, the upper face of the said body also including a downwardly inclined portion that extends from the crown portion to the upper edge of the said concaved wall, 20 the said body portion also having a concaved socket in its lower face in vertical alignment with the crown portion of the body, a spherical bearing for seating in the concaved socket of the body and a pull member 25 connected to the said bearing.

ALBERT ELLISON LINEBERG.
